REINFORCED SAFETY TOOL HANDLE

Filed Oct. 8, 1928

UNITED STATES PATENT OFFICE

EDWARD COHN, OF BROOKLYN, NEW YORK

REINFORCED SAFETY TOOL HANDLE

Application filed October 8, 1928. Serial No. 311,113.

This invention relates to reenforced safety tool handles, and has among its objects the provision of tools having improved handles which have strong engagement with the heads of the tools.

Another object of the invention is to provide a device of the character described in which the handle is made of a relatively light material, as for example, wood, and has running therethrough a rod of metal, there being an anchor member mounted in improved engagement with the head of the tool and having abutment relation with the head of the handle, the said rod strongly interconnecting the anchor member and the handle and tending at all times to reliably secure the handle to the head of the tool.

Another object of the invention is to construct a device of the nature set forth in which a tool such, as for instance, a hammer having a usual heavy head and a wooden handle extending into an opening therein, there being an anchor member in one end of the opening opposite the handle, the said anchor member having abutment engagement with the head of the hammer, and tension means being furnished engaging the anchor member and tending to draw the handle strongly into the opening in the head of the hammer.

A further object of the invention is to provide a device of the character set forth having comparatively few and simple parts which are inexpensive to manufacture, the said parts being easily assembled to form a strong and reliable construction and one which is of a conventional, neat appearance.

By this invention it is sought to strongly connect the tool head with the handle through a tension rod and strong elements at the tool head, which elements are individually rigid and yet co-operate for a uniform bearing action due to the tension, and equalize the strains, while affording a slightly yielding co-operation under excessive shock.

It will be appreciated that while I show a number of different embodiments or variations of the invention, that essentially the same principle is employed throughout. Furthermore, while the invention is shown

as being particularly applied to a hammer, it is clear that it may be used with tools of various types, and that wherever necessary slight changes may be made in construction and mounting of the handle to adapt it for use with various kinds of tools.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated on the annexed drawing, wherein like parts are designated by the same reference characters throughout the several views.

In the drawing:

Fig. 1 is a perspective view of a device embodying the invention.

Fig. 2 is a top view of a modified tool handle.

Fig. 3 is a longitudinal section of Fig. 1.

Fig. 4 is a perspective view of a detail of the invention, showing an anchor member for the tool handle.

Fig. 5 is a fragmentary top plan view of a modification of the invention, showing a different anchorage for a tool handle.

Fig. 6 is a sectional view taken on line 6—6 of Fig. 5.

Fig. 7 is a similar top plan view of a modification of the invention showing the upper portion of the tool handle.

Fig. 8 is a sectional view of the same taken on line 8—8 of Fig. 7.

Fig. 9 is a similar top plan view of a modification of the invention, corresponding to that of Fig. 2.

Fig. 10 is a section of the same taken on the line 10—10 of Fig. 9, and showing a part of the tool handle.

Fig. 11 is a sectional view of a modified nut for the re-enforcing rod.

Fig. 12 is a bottom plan view of the same.

Fig. 13 is a fragmentary view of a modified handle re-enforcing rod as applied to an axe or hatchet.

Fig. 14 is a fragmentary plan view of a

further modification showing a similar application.

Fig. 15 is a top plan view of a detail of the invention shown in Fig. 14.

Fig. 16 is a plan view of a detail of invention shown in Figs. 9 and 10.

Fig. 17 is a fragmentary top plan view of a still further modification of the invention.

Fig. 18 is a sectional view thereof taken on line 18—18 of Fig. 17.

Fig. 19 is a fragmentary perspective view of a modified form of a tool handle re-enforcing rod anchorage for an axe or hatchet.

Figs. 20, 21, and 22 illustrate further modifications of anchorages for the tool handle.

Fig. 23 is a fragmentary sectional view taken on the line 24—24 of Fig. 20.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Generally described, the invention provides a re-enforcing safety tool handle which is made of wood and is anchored in an improved manner to the head of the tool. The means provided by my invention serves on the one hand to increase the strength of the handle, and, incidently, the weight thereof where this may be desirable. Furthermore, the said means strongly connects the handle with the head of the tool, this latter purpose being aided by an improved anchorage which has abutment relation with the head of the tool which seats against an end of the handle. One element of the anchorage may take the form of a cross, and the head of the tool may be recessed to receive the ends or points of the cross. Coacting with this element between the arms thereof is a member which may be either in the nature of a soft metal, as, for example, solder that is filled into the portions of the opening of the head of the tool about the cross, or it may be cast integral with the head of the tool, thus providing an opening in the tool which conforms to the shape of the cross and in which the latter seats as aforesaid. Within this basic principle, various modifications may be made, a number of which are illustrated in the drawings. The invention, however, is not to be construed as limited to the precise features of construction shown, but alterations, modifications, or changes within the scope of the invention may be made. Thus, for example, while the re-enforcing rod for the handle is shown in one particular instance having

headed engagement with the anchorage, and in another instance having threaded engagement therewith, it will be understood that in each of the modifications shown, the connection may be either riveted, welded, or threaded. Further, if desired, the points of the cross may be welded in the said recesses. Additional anchor means for the re-enforcing rod for the tool handle may take the form of a circle with arms at right angles that may engage the plate having recesses therein either above or below the plate and rigidly secure the rod thereto.

Referring in detail to the drawing, 20^a denotes a device embodying the invention. The same includes a tool handle 21 having a

lower main portion 22 that is adapted to be gripped by the hand of the operator and an upper portion 33 which constitutes an anchorage. The latter is adapted for engagement with any device as may be found necessary or desirable preferably in connection with parts of tools of various types.

In the drawing herein disclosed the said tool handle is shown as used in conjunction with a hammer head 24, but it is understood that this is shown merely as illustrative of the invention and is not to be construed in a limiting sense. The tool handle 21 has an axial opening 25 extending longitudinally thereof, and in the said opening is a re-enforcing rod 26 extending substantially from end to end of the tool handle. While the tool handle may be made of any suitable material that possesses the requisite strength and toughness, yet it will suffice to represent the same as being made of wood. On the other hand, the rod 26 is made of a metal that reinforces the tool handle and is also capable of exerting a tension thereon in a longitudinal direction as hereinafter more particularly described.

At the upper portion of the tool handle, the latter has engagement by means of the rod 26 with the anchorage 33, this engagement being provided by threaded, welded, or riveted means. In fact, the rod 26 may even be differently secured with the anchorage 33 and any particular means of connection set forth hereinafter is intended to be merely illustrative, and not to limit me as to the scope of the invention.

At its other end, the rod 26 is threaded as shown at 27, the thread having engagement with a cylindrical nut 28 that sets into a recess 29 of the tool handle. A washer 30 may be interposed between the nut 28 and the closed end of the recess. One end of the nut may be formed with a kerf 31 for engagement by means of a screw driver so as to permit any desired tension to be exerted on the rod 26 in order to increase the snugness of the engagement of the anchorage 33 with the body 22 of the tool handle.

The anchorage 33 of the tool handle meets

with the inner end 32 of the latter and may be of different forms, only a few of which are shown in the drawing. One form of the anchorage may consist of a cross member 33 having a plurality of arms 34 along axes that intersect at right angles and lie in a plane perpendicular to the tool handle. The cross member 33 has a central hole 35 which is countersunk at 36 to receive the head 37 and may be welded to the anchor member 33. Furthermore, the anchor member 33 can be secured to the re-enforcing rod by a threaded or riveted connection. The hammer head 24 or similar portion of any other tool that might be used has an opening 38 therein which is tapered to receive the inner end 32 of the tool handle, and to have wedge engagement therewith. There is also an opening 39 in the upper end or face of the head of the hammer or tool to receive the anchorage 33, the opening 39 including a plurality of recesses 40 receiving the arms 34 of the cross member. Separating the openings 38 and 39 is wall or partition 41 that constitutes a seat coacting with the underside of the anchor member 33. The wall 41 is centrally perforated to permit the passage therethrough of the re-enforcing rod 26. It will now be seen that on turning the nut 28, the parts of the tool handle are drawn tightly together with a high degree of tension so that the safety of the tool handle is rendered a maximum. More particularly, the head of the tool handle is strongly engaged against loosening due to repeated and strenuous use.

In Figs. 5 and 6 is shown a modification of the tool handle, and more particularly relating to the anchorage thereof. In this modification, the head 45 of the tool handle is formed with a through opening 46 that is of substantially rectangular shape in cross section and which tapers from the upper to the lower end thereof. The body portion 47 of the tool handle is inserted into the lower part of the opening 46, while the cross member 48 of the anchorage is inserted into the top portion of said opening, the head of hammer being recessed at 49 to receive the ends of the arms 50 of the cross. Interposed between the inner end of the tool handle body portion and the underside of the cross member is a plate 51 of the nature of a washer. Filling the space between the sides of the arms 50 and the walls of the opening 46 and above the plate 51 is solder 52 or other similar substantially soft metal. If necessary, the underside of cross 48 can also be formed with any suitable projections or teeth so as to hold the solder with the maximum reliability. In practice, it is intended that the plate 51 be first inserted into the opening 46 followed by the inner end of the tool handle body, and thereafter the cross member is mounted in position. Finally, a re-enforcing rod such as that hereinbefore shown at 26 is inserted

through the holes 53 and 54 in the cross member and in the plate 51, thence through the body of the tool handle, and finally locked at the lower end of the latter with a screw driver. Here again it will be noted that the particular means of connection as between the cross member and the rod 26 can be of various types, whether riveted, welded, or threaded.

In Figs. 7 and 8 is shown a further modification of a tool handle relating more particularly to the anchorage thereof. The principle involved in this modification is similar to that of the foregoing devices. In this modification the head 55 of the tool handle has an oblong opening 56 which receives in its upper portion an anchor plate 58 which is substantially rectangular in form, but having semi-circular projections 59, or the like, that extend into similar recesses 60 in the walls of the said opening. While the plate 58 is approximately coextensive with the opening 56, the projections 59 extend therebeyond and seat at 61 so as to form a proper abutment to take up the tension on a re-enforcing rod 62. Connected with the plate 58 is a sleeve 63 having threaded engagement at 64 with the upper end of the reenforcing rod 62 of the tool handle. The sleeve 63 is undercut to form a neck portion 65 that extends through a hole 66 in the anchor plate and the top of rod 62 is headed over into a countersink of the plate and may be riveted down as in 65 of Fig. 7. The body 57 of the tool handle is of course recessed as shown at 67 to receive the sleeve 63 and a washer 68 may be placed between the inner end of the recess and the lower portion of the sleeve 63. While the sleeve 63 has been shown as having headed engagement in the anchor plate, this engagement may also take the form of a threaded or welded connection. In this modification a cross member as shown in connection with Figs. 1 and 5 may also be used and similarly it will be understood that the sleeve members may, if desired, be used in conjunction with the said cross member.

In Figs. 2, 9, 10, and 16 is shown the primary modification of the invention. According to this modification, the tool handle has a particularly reliable anchorage which cooperates with a tool head 70 having a through opening 71 receiving an end of a tool handle body 72. In the upper end of the opening 71 is positioned an anchor plate 73 which may be approximately one-quarter inch in thickness and having projecting lugs 74 at the sides thereof that extend into corresponding recesses 71^a at the sides of the said opening and seat snugly therein. Set into the anchor plate 73 is a cross member 75 having a circular body 76 which is countersunk at 77 and from which extend the arms 78. According to this construction the upper end of the tool handle anchorage is flush with the top surface of the head of the tool. A re-enforcing rod such

as 26 passes through the opening 79 in the cross member 75 and with the top of the rod headed over seats in the countersink 77. The rod is thus brought under tension to strongly secure together the several parts of the tool handle as heretofore mentioned. The plate 73 may be of a metal that possesses a high degree of toughness, while the cross member 75 is of a metal that is comparatively 10 very hard so as to afford the proper anchorage for the re-enforcing rod. Furthermore, the said rod may be connected in various ways to the cross member, although according to this construction, the rod, the plate 73, and 15 the cross member 75 are separate and upon being assembled together are retained in snug engagement by the tension on the rod.

In Figs. 11 and 12 is shown a modification of the nut for the re-enforcing rod, said modification providing a nut 80 which has a through opening 81 that is threaded for engagement with the threaded portion of the re-enforcing rod 26. At its lower end are provided a plurality of kerfs 82 intersecting at 25 right angles. In all other respects the nut 80 is similar to the nut 28 and operates in a like manner.

In Figs. 13, 14, 15 is shown a modification of the re-enforced safety tool handle as applied to axe or a hatchet. Thus the form of the opening may be elliptical, rectangular or may be curved at both ends or with one end smaller than the other as shown in Fig. 14. Thus the tool head 83 has an elliptical opening 84 which seats a plate 85 through the intermediacy of lugs 86 thereon according to the principle hereinbefore described. The re-enforcing rod 87 is headed over as shown into the countersink in the plate. In Figs. 40 14 and 15 the tool head 88 has an opening 89 receiving a plate 90 that seats therein in any suitable manner. The plate 90 may however 45 also be provided with lugs as in Fig. 13 that set into recesses in head 88. To afford a most reliable connection between the tool handle, re-enforcing rod, and the plate 90, the latter is recessed to receive a connecting member 91 that may be of comparatively hard metal and has a pair of arms 92 seated in the recess 50 of the plate 90. Member 91 is countersunk at 93 to receive the head of the rod aforesaid which passes through the hole 94.

In Figs. 17 and 18 is shown a further modification of a tool handle which will be understood to be generally similar in the conformation of parts to that disclosed in Figs. 9 and 10 except that the co-operating parts are welded together into one unitary construction. More specifically, the anchor plate 60 95 and cross 96 positioned therein and the re-enforcing rod 97 engaging the cross member may be subjected to heat and pressure and united along their meeting edges. Of course if desired, the lugs 98 of the anchor 65 plate may be welded to the tool handle head

99 in the recesses 100 of the latter. This latter may be employed also in the modifications hereinbefore described.

In Fig. 19 is shown a further modification of the invention wherein a tool handle reinforcing rod 101 has an undercut or annular notch 102 with a transversely extending anchor plate 103 engaging the rod 101 at the said notch in the adjacent portions of the said plate forced into engagement with the notch. Here of course soldering may be resorted to. This device is adapted to be used in an axe or hatchet in the same manner as shown in Figs. 13 and 14. Of course the connection as between the rod 101 and the plate may be strengthened by heading over the upper end of 104 of the rod.

In Figs. 20 and 23 is shown a still further modification of a tool handle, the same comprising an anchor plate 105 which is of substantially oblong form to set into a corresponding opening in a tool handle head 106, the said anchor plate having lugs 107 at the sides thereof functioning as hereinbefore more particularly set forth. Coacting with the re-enforcing rod 108 is a circular plate 109 which is set into a recess in the plate 105, the circular plate 109 being integral with or welded to the rod 108 to fit snugly in place, and a suitable washer 109a being interposed 95 beneath the circular plate 109 and the bottom of the recess receiving the same.

In Figs. 21 and 22 are shown still further modifications of tool handles having anchor plates 110 and 111, respectively, the former being of star shape and the latter being of circular shape. The re-enforcing tool handle rods 112 and 113 have connection with the plates by either threading, welding, or riveting means.

I claim:

1. In a tool handle, a handle, a tool head having a comparatively large opening extending entirely therethrough to receive an end portion of the handle, a thin plate in said opening at the end of the handle, said plate having a plurality of projecting lugs in the plane thereof, said tool head having recesses at said opening to receive and afford seats for the lugs, said lugs providing the sole support for said plate in said seats, with the outer face of the plate flush with the adjacent face of the tool head, a metallic rod extending through the handle and the plate and having a comparatively large head, said plate being countersunk to receive the head of the rod, said head affording a uniform bearing action on the plate to equalize strains, and tension means engaging the other end of the rod to cause the latter to draw tightly on the plate at the lugs thereof and cause the handle to be reliably retained in engagement with the tool head.

2. In a tool handle, a handle, a tool head having a comparatively flat end surface and

a relatively large opening extending entirely therethrough and communicating with said surface, said opening receiving an end portion of the handle, a comparatively thin plate
5 adapted to be received in said opening and to lie substantially at right angles to the said handle, and adjacent to the end thereof, said plate having projections at the edges thereof and said tool head having recesses from said
10 opening to receive the projections and thereby prevent movement of the plate inward into the tool head, said projections providing the sole support for the plate in said recesses, a rod extending through the handle, said rod having engagement with the plate, and an anchorage for the rod at the other end of the handle to place the rod under tension and secure the handle in the tool head, the said plate seating even with the said flat surface
15 of the tool head, and there being a substantial length of the handle received in the tool head.
20

Signed at Brooklyn in the county of Kings and State of New York this fourth day of
25 October, A. D. 1928.
